UNITED STATES PATENT OFFICE.

EMIL MARSCHNER, OF GROSSPRIESEN, AUSTRIA-HUNGARY, ASSIGNOR TO
THE FIRM OF SCHELLING & STAUBLI, OF HORGAN, SWITZERLAND.

DEVICE FOR HOLDING THRUMS OR KNOTTING-THREADS IN LOOMS.

No. 836,518.

Specification of Letters Patent.

Patented Nov. 20, 1906.

Application filed June 12, 1905. Serial No. 264,887.

To all whom it may concern:

Be it known that I, EMIL MARSCHNER, a subject of the Emperor of Austria-Hungary, residing at Grosspriesen, Austria-Hungary, have invented new and useful Improvements 5 in Devices for Holding Thrums or Knotting-Threads in Looms, of which the following is a specification.

The present invention has for its object a 10 device whereby the thrums or knotting-threads required in the working of a loom are always held flat and parallel to each other within readily convenient reach of the operator, so that when a knotting-thread is 15 required it can be drawn from the right or left or even from the middle of the device without disturbing the other knotting-threads in the slightest.

The improved device has two spring-clamps 20 adapted to be arranged on the overlay-beam of the loom, each clamp consisting of a leaf-spring and two curved springs arranged one on each side of the leaf-spring, so that the latter can play freely between them, 25 the three springs of each clamp being connected with each other at one end, but being free at the other end. For the purpose of facilitating the mounting, removal, and shifting of the spring-clamps they are arranged 30 on sheet-metal strips which catch under and over the overlay-beam and are clamped against the lower flange thereof by springs.

The accompanying illustrative drawings 35 show one construction of the improved device, Figure 1 being a side elevation, and Fig. 2 a front elevation thereof.

To the usual overlay-beam 1 of the loom are secured two spring-clamps at a suitable 40 distance from each other, each of which consists of a reversely-curved leaf-spring 2 and two curved springs 3, arranged one on each side of the leaf-spring 2, so that this latter can move freely to and fro between the two 45 curved hook-shaped springs 3, Fig. 2.

The knotting-threads, which lie flat and parallel to each other, are laid in between the springs 2 and 3, for which purpose the free ends of these springs are adapted to be 50 pressed inward or outward, as shown in dotted lines in Fig. 2. The ends of the bundle of knotting-threads are laid transversely to the longitudinal direction thereof, as shown in dotted lines in Fig. 1, through the

intermediate space between the free ends of 55 the springs, and the springs are then allowed to snap together, so that they take up the position shown in full lines in Fig. 2. The several knotting-threads, whose ends project freely from the spring-clamps and the middle parts of which lie free between the spring-clamps, can then be seized at one end or the other or even at the middle between the two 60 spring-clamps and simply drawn out without disturbing the remaining threads of the 65 bundle in their parallel position or appreciably shifting them in the spring-clamps. These spring-clamps may be attached to the overlay-beam of the loom in various ways, conveniently, for example, in the manner 70 shown in the drawings, where the clamps are arranged on sheet-metal strips 4, which lie against the lower flange of the overlay-beam and catch with their rear turned-up end 5 behind the web of the beam and are clamped 75 against the lower flange of the beam by springs 6, which bear against the upper side of the lower flange and against the front of the web of the beam. The springs 2 3 6 may be conveniently constructed of sheet metal. 80 This method of attaching enables the spring-clamps to be easily mounted and removed and conveniently adjusted to suit the length of the knotting-threads desired.

The present device, while exceedingly 85 cheap to construct, effectively holds the knotting-threads always within convenient reach of the operator, and thus renders the attendance of the loom easier, so that the output is augmented. Moreover, it is very 90 easy to charge the device with the desired threads.

Having now particularly described and ascertained the nature of the said invention and in what manner the same is to be performed, I declare that what I claim is— 95

1. A device for holding knotting-threads comprising a pair of coöperating springs forming a clamp adapted to be mounted on the overlay-beam of the loom and between 100 which spring the knotting-threads are held, substantially as described.

2. A device for holding knotting-threads in which the clamps each consist of a leaf-spring and two curved springs arranged one 105 on each side of the leaf-spring so that the latter can work freely between them, the three springs of each clamp being connected to

2
each other at one end, but being free at the other end, substantially as hereinbefore described.

3. A device for holding knotting-threads comprising spring-clamps mounted on sheet-metal strips which catch under and behind the overlay-beam and are clamped against the lower flange thereof, substantially as hereinbefore described.

10 4. A device for holding knotting-threads comprising a leaf-spring and a hook-shaped spring at each side thereof, the ends of said spring free to move, a support for the springs including means to detachably connect them to a beam, substantially as described.

15 5. A device for holding knotting-threads, comprising a reversely-curved spring, and hook-shaped springs at each side thereof,

means to support the springs comprising a member 4 and a spring member 6, substantially as described.

6. A device for holding knotting-threads, comprising a spring reversely curved at its free end, a hook-shaped spring at each side thereof, means to support the springs comprising a member 4 and spring members 6 formed in one piece with the hook-shaped springs, substantially as described.

In testimony whereof I have signed my name to this specification in the presence of two subscribing witnesses.

EMIL MARSCHNER.
